J. S. MAXWELL,
AUTOMATIC PIANO PLAYER ACTION,
APPLICATION FILED AUG. 26, 1919.

1,358,455.

Patented Nov. 9, 1920.

UNITED STATES PATENT OFFICE.

JOHN S. MAXWELL, OF RICHMOND, INDIANA, ASSIGNOR TO STARR PIANO COMPANY,
OF RICHMOND, INDIANA, A CORPORATION OF INDIANA.

AUTOMATIC PIANO-PLAYER ACTION.

1,358,455.

Specification of Letters Patent.

Patented Nov. 9, 1920.

Application filed August 26, 1919. Serial No. 319,940.

To all whom it may concern:

Be it known that I, JOHN S. MAXWELL, a citizen of the United States of America, residing at Richmond, in the county of Wayne and State of Indiana, have invented certain new and useful Improvements in Automatic Piano-Player Actions, of which the following is a full, clear, and exact description.

In the past for a number of years, upright pianos have been equipped with automatic player attachments comprising a bank of small pneumatics operated from a suitable wind chest through the instrumentality of a perforated music sheet traveling over a tracker bar. It has been customary to associate the entire automatic player action in a single unitary structure which is adapted to be inserted into and withdrawn from the piano case above the key board, without any change, adjustment or alteration of the piano action or any of its correlated parts.

The pneumatics, usually when deflated, close, and to the movable part or leaf is attached a rod or other suitable device which, in rising, strikes either the piano action wippens, or the abstracts connected therewith, and thereby plays the instrument automatically and independently of the keys when played by hand.

Much ingenuity has been expended in efforts to improve the character and functions of such automatic players, the problems being mainly to contract the parts into the smallest available compass, to improve the leverage between the pneumatics and the wippens, to provide for a better tone and to cheapen and simplify the construction, and I have worked along these lines to develop a better form of action than those heretofore used.

I have accordingly devised a player action which is distinguished by the following novel features. The pneumatics are connected by suitable rods or wires with levers pivoted to the frame of the automatic action, and when deflated raise such levers into contact with stops set in short levers pivoted to the piano abstracts, and having their free ends resting on a stationary bar, so that when raised by the pneumatics they throw the wippens and strike the piano strings.

The levers connected with the pneumatics normally rest upon cushions on the stationary members of the said pneumatics, and have limiting stops by which their range of

movement is controlled. The connections between said levers and the pneumatics are also adjustable as to length, and the stops set in or affixed to the levers pivoted to the abstracts are also adjustable; so that a perfect adjustability of all the parts is fully provided for.

So much of this action as is necessary, in view of the wide knowledge now existing as to the prior art, to an understanding of my improvement is illustrated in the accompanying drawing which shows one of the pneumatics and illustrates its relation to the piano action.

In this drawing A designates a stationary part of the player action to which is secured the upper or stationary leaf B of the pneumatic. The movable leaf or element of the pneumatic is designated by the letter C, and for greater rigidity and convenience an arm D is secured to the part A and extends horizontally, and from this depends a brace E secured to the upper element B. A small block F with a cushioned top is secured to the said element and affords a seat for a lever G pivoted to the part A.

To the end of this lever is pivotally connected a rod or wire H which is adjustably connected to an arm or extension I from the movable element C, and on the upper side of the lever G is a projection J which, when the player action is inserted in place, lies immediately under a stop K adjustably secured to a lever L pivoted to the piano abstract M. The rear end of this lever is rounded or provided with a rounded projection N which normally rests upon a cushioned seat on a stationary bar O secured in the piano case.

This is the construction of each pneumatic and its correlated parts. The said pneumatics may be in banks, or otherwise disposed, in order to have the necessary room for performing their allotted functions. The levers L may be secured to the abstracts at any preferred point. That is to say, they may be above the pneumatics, or below them, and in case they are below it is only necessary to turn the pneumatics over so that they will pull up instead of push up the abstract lever.

This device has been found to give the most satisfactory results, and to be greatly superior to others heretofore in use. One of its principal advantages follows from the marked mechanical advantage secured by

the system of levers intermediate the pneumatics and the wippets, and to the fact that the space between the front and rear of the piano case is very markedly decreased without sacrifice of this mechanical advantage.

My invention resides, as will now be apparent, in the details of the construction which I have above described, and what I therefore claim is:

- 10 1. An automatic piano player action comprising as one of its parts a controllable pneumatic having a movable element, a lever pivoted to the action frame and connected with the said movable element, in combination with a piano abstract, a lever pivoted thereto with its one end resting on but movable away from a stationary stop, and a stop secured to said lever and lying immediately over the lever actuated by the pneumatic.
- 15 2. An automatic piano player action comprising as one of its parts a controllable pneumatic having a movable leaf or element, a lever pivoted to the action frame, a stationary stop on which said lever normally rests,
- 20
- 25

a connecting rod between the end of the lever and the end of the movable element of the pneumatic, in combination with a piano abstract, a lever pivoted thereto, and having one end resting on but unattached to a fixed 30 stop, a stop secured to said lever and lying normally over the pneumatically controlled lever at a point between its fulcrum and point of connection with the pneumatic.

3. The combination with the support or 35 frame of an automatic player action of a pneumatic secured thereto and having a movable part, a lever pivoted over the pneumatic, a rod connecting the end of the movable part with the end of the lever, a piano 40 abstract, a lever pivoted thereto but free at its ends and adapted when raised to raise the abstract, and a stop secured to said lever over a point in the pneumatically controlled lever between its fulcrum and its point of 45 connection with the pneumatic.

In testimony whereof I hereunto affix my signature.

JOHN S. MAXWELL.
